Nicholas R. Ariesan, Milwaukee, Wis.

Application December 30, 1944, Serial No. 117,177

Term of patent 7 years

(Cl. D48—27)

To all whom it may concern:

Be it known that we, Evans J. McEachron, Irwin M. Glisch, and Nicholas R. Ariesan, citizens of the United States and residents of Milwaukee, in the county of Milwaukee and State of Wisconsin, have invented a new, original, and ornamental Design for a Pocket Lighter, of which the following is a specification, reference being had to the accompanying drawing, forming part thereof.

We claim:

The ornamental design for a pocket lighter, as shown.
